[57] **CLAIM**

The ornamental design for a portable hand held data entry terminal, as shown and described.

DESCRIPTION

FIG. 1 is a top, front, right side perspective view of a portable hand held data entry terminal showing my new design;

FIG. 2 is a top plan view thereof on an enlarged scale;

FIG. 3 is a left side, elevational view thereof on an enlarged scale;

FIG. 4 is a right side, elevational view thereof on an enlarged scale;

FIG. 5 is a front elevational view thereof on an enlarged scale;

FIG. 6 is a rear elevational view thereof on an enlarged scale;

FIG. 7 is a bottom, plan view thereof on an enlarged scale;

FIG. 8 is a top, front, right side perspective view of a second embodiment of my design;

FIG. 9 is a top, plan view thereof on an enlarged scale;

FIG. 10 is a left side elevational view thereof on an enlarged scale;

FIG. 11 is a right side elevational view thereof on an enlarged scale;

FIG. 12 is a front elevational view thereof on an enlarged scale;

FIG. 13 is a rear elevational view thereof on an enlarged scale;

FIG. 14 is a bottom, plan view thereof on an enlarged scale.
